ABSTRACT: This disclosure concerns a device for supplying electric current to machines moving along one or several guide rails in which one or several linear conductors and a unit of current outlets are urged constantly by elastic members against and rub on one or several conductors, the assembly formed by the unit and a core carrying the conductors having a certain freedom of transverse movement relative to the guide to which the core, which is itself rigid or flexible, is secured in a flexible or rigid manner.

Fig. 5

DEVICES FOR FEEDING ELECTRIC CURRENT TO MOBILE ELECTRIC MACHINES

The two principal successively used ways of supplying current to carriages supporting movable machines such as blocks, hoisting apparatus, portable tools etc. having wheels and rolling on open or closed aerial rails are, on the one hand, a flexible wire moving with the carriage and following the movements thereof, wire which is flexible and possibly in coils guided by the track itself or outside the same, and on the other hand, linear conductors which are external or internal to rails and are rigidly integral therewith and on which bear permanently current outlets integral of the carriage.

The device with inner linear conductors with single track used most usually has various drawbacks. On the one hand, these conductors and the continuous or interrupted insulators which support them, themselves fast on the rail, occupy a certain space. The total space of the two conductors is further increased by the standards existing in certain countries and referring to the mutual spacing of the two conductors separated by air or mounted on the same insulator, standard which have for purpose to avoid the creation of sparks. In the case where these conductors are in a high position, hooked to the upper part of the rail, the diameter of the metallic wheels of the carriage, on a horizontal shaft, is reduced bearing in mind the volume occupied by the conductors, their insulators and the minimum space tolerated between the wheels and the conductors. However, it is known that the rolling is all the better as the diameter of the wheels is greater. In the case where the conductors are laterals, that is to say supported by insulators hooked to the lateral walls of the rail, the same space requirements previously mentioned lead to the placing of the wheels in a very close manner in the middle of the rail which is harmful this time to the stability and increases the working rate in the ways by increasing the stresses.

It is also possible to use wheels made of electrically insulating material, plastics for example, but the maximum carrying load, for the same diameter wheels is less than that tolerated by using metallic wheels.

It is evidently possible to palliate to these drawbacks in various ways. It is for example possible in the case of conductors in a high position to provide the wheels with caps of the mudguard type of insulating material, which makes it possible to bring them closer to the conductors beyond the standard distance. It is also possible to make the rails wider or longer in such a way as to increase the diameter or the spacing of the wheels. In those cases the effect on the cost of material is immediate.

It has been sought to avoid this last drawback by making conductors inwardly positioned with a current outlet plug conceived in such a way that it receives within it these conductors. The space saving is evidently immediate. However in such devices the conductors being rigidly connected to the insulating sheath which supports them and the current outlets being connected rigidly to the carriages, the contact between them and the conductor can be bad in particular in curved areas. These current outlets have been made floating by providing them with return springs which ensure constant contact with the conductor along a given direction. This unidirectional mobility constitutes an additional degree of freedom relative to the conductor but is insufficient to ensure a good contact.

The object of the present invention is an improvement in devices for supplying electrical current to machines moving in or along one or several guide rails, devices comprising one or several linear conductors connected to the rail on which rub current outlets constantly brought in contact with conductors by elastic means, improvement characterized by the fact that the current outlet unit receives the core carrying the conductors within it and that either because the core is flexible or because its connection with the guide rail is flexible, or because the unit is movable along several directions within the space comprehended by the carriage, the assembly constituted by the current outlet unit and the core carrying the conductors has several degrees of freedom relative to the carriage and to the guide rail.

By way of nonlimiting example there will be described now the application of the improvement according to the invention to a carriage carrying a hoisting apparatus and moving by means of carrying rollers along an aerial monorail, with the aid of the accompanying drawing in which there can be seen:

FIG. 1 is a general vertical cross-sectional view perpendicular to the direction of the monorail of the device according to the invention.

FIG. 2 is a perspective view of the suspended core.

FIG. 3 a perspective view of the unit carrying the contacts in their cradle.

FIG. 4 a vertical cross-sectional view perpendicular to the direction of the monorail for a modification of the device according to the invention which has two cores.

FIG. 5 a cross-sectional view perpendicular to the rail for a modification where the unit rests on an intermediate curved seat.

In FIG. 1, reference 1 designates in schematic fashion a cross section of the monorail carrying two horizontal flanges 2 and 3 on which can roll roller 4 and 5 supporting the apparatus. These roller rotate about the axis $x'-x$ through wheel beds 6 and 7 and a cradle, of any shape, here parallelepipedal, 8, is connected to axles 9 and 10 of the wheel beds by suitable means not forming a part of the present invention. A central core 11 connected to the upper side of rail 1 by a skirt 14 surrounded by a sectional interfitment 12 cooperating from place to place with prismatic cages 13 of the same shape as the interfitment 12, themselves connected to side 1 of the rail by any devices, for example by pins 15. The assembly of this support formed of skirt 14, of interfitments 12, of cages 13 and of pins 15 ensures a link between plate 11 and side 1 of the rail which can be either rigid or flexible and allowing core 11 to have a pendular movement (arrow W) relative to side 1, according to the desired modification. Naturally the hooking device of core 11 to the upper side 1 of the rail, here described, is only given by way of simple example, all other devices leading to the same rigidity or, to the contrary, to the same freedom of pendular movement of core 11 can be used without departing from the scope of the invention. In particular it can be seen by referring to FIG. 4 that there can be substituted for the assembly 12, 13, 14 and 15 previously mentioned one or several hooks 12' passing through openings provided in skirt 14, from place to place, hooks which may be welded or fastened under side 1 of the rail, which side is then entirely full.

On core 11 have been secured on both sides or on only one side conductive lines 16, 17, 18, 19 in variable number. These lines can be ordinary conductors of copper or of molybdenum, copper-aluminum or other materials secured by any suitable means to core 11 or can be made by projecting on said core 11 with a gun or with a plasma gun and a continuous band the previously mentioned conductors reduced to a powder or to a paste. Core 11 can be of insulating material in which case the conductors can be applied directly thereon or can be made of material having variable conductivity in which case an insulating material will be interposed between conductors 16, 17, 18, 19 etc. and core 11.

According to the invention there rests in cradle 8 a block 20 of preferably insulating material such as bakelite in which has been provided a groove 21. Core 11 is engaged in this groove in such a way that its conductive bands 16, 17, 18 etc. face an equal number of current outlets 22, 23, 24, 25, etc. urged thereagainst by elastic members, here springs 26.

According to the invention core 11 can be either rigid and rigidly connected to side 1 or flexible and able to back and rigidly connected to face 1, or rigid but connected in flexible manner to side 1 in such a way that it can be given a pendular movement (arrow W), or at once flexible, able to back, and connected flexibly to side 1. In conformity with the general characteristic of the present invention, block 20 is then according to cases:

a. simply placed inside cradle 8 and very light and able to move with a sufficient amplitude inside said cradle when the

core is rigid and rigidly connected to its side 1 or even when it is rigid and connected to side 1 in such a way as to have a pendular movement (arrow W).

b. fixed or very slightly movable within cradle 8 when the core is rigidly connected to side 1 but flexible and able to back itself or at once flexible and able to back and flexibly connected to side 1.

In this way, the best contact is constantly ensured between the contactors or current outlets 22, 23, 24, 25, and the conductors located on core 11. Regardless of the relative movements of one part of core 11 relative to the rail and/or to the carriage and the other part of the cradle 8 relative to the rail and to core 11, contact remains perfect between the conductors and the current outlets.

Referring to FIGS. 2 and 3 there are seen in perspective the elements previously described. Core 11 can have excrescences of variable shapes. The device for fastening the core to wall 1 is discontinuous from place to place. It can be continuous by welding or fastening on the upper side. Core 11 can have excrescences such as projection 27 for the purpose of lengthening the leak between two superimposed conductors 17 and 18. It is known that in effect there is reason for allowing a certain space between two conductors separated by free air, and between two conductors secured on the same insulator a greater space is required to avoid the formation of sparks. Certain countries have standardized these spaces in particular to 11 millimeters for conductors separated by air and to 37 millimeters for conductors carried by the same insulator. Consequently if the distance between conductors 17 and 18 is less than the standard distance of 37 millimeters a projection of type 27 should be provided in order to bring the leak line to this length.

In FIG. 3 there are seen two current outlets 23, 23', and 24, 24' constantly urged by spring couples 26a, 26b, 26'a, 26'b, toward continuous conductive bands 17 and 18 of core 11. All other current outlet devices and all other means for stressing these can be used without departing from the framework of the present invention. Block 20 is simply positioned on the floor of cradle 8 and can move, its movements are limited by vertical skirts 8a, 8b, etc. of the cradle.

Due to the device according to the invention, there can be seen by referring more particularly to FIG. 1 that rollers 4 and 5 in the shape of wheels can occupy the entire height of rail 1. This makes it possible to increase to a maximum their diameter within a same rail which improves the rolling coefficient all the more that there are used on the contrary wheel beds which are smaller to those of rollers 4 and 5. The spacing also favors more a good stability. Block 20 being preferably of insulating material, for example of bakelite, the problem of distance between rollers 4 and 5 and the conductors and contactors is also resolved, which makes it possible eventually in the measure where stability is not a factor to reduce the width of rail 1.

Core 1 and the conductors it carries can be made at a greatly decreased cost in particular if continuous conductive bands as indicated above are provided by spray guns or plasma guns. Core 11 can then be directly made of plastic material by molding, extrusion, injection, covered by its conductors, and cut off according to the needed sizes of the place where the machine is to operate; once secured in the place it can also be cut off, twisted or modified according to other needs.

Another important advantage of the device according to the present invention relates precisely to the possibility for core 11 according to one modification to twist itself. As indicated above, if core 11 can thus twist itself and is connected flexibly to the side 1 of the rail, block 20 can be secured in semirigid fashion to the cradle 8. Besides, and especially according to the prior-art technique with upper or lateral rigid conductors fixed rigidly to the sides of the rail, it is necessary, to avoid in curves relative movements of the machine with respect to the rail, to provide a large contact area between the current outlets and the conductors. This requires either the use of very large current outlets or the use of devices urging the current outlets on the conductors permitting a considerable move-

ment of the current outlets. The effect on the cost is immediate. The invention thus with respect to this brings about an essential new industrial advantage since the relative movements of the carriage in curves are palliated in absolute manner thanks to the mobility of the assembly formed by the block carrying the current outlets and by the core carrying the conductors, which are essential characteristics of the present device.

There has been shown finally in FIG. 4 a modification, among others, of the device according to the invention in which block 20 is replaced by a block formed of two parts 20a and 20b comprising two grooves 21a and 21b in which are housed two cores 11a and 11b which are identical to core 11 above described. To each of these two cores correspond two groups of current outlets urged towards one another by two groups of flexible members. Cores 11a and 11b are secured to the upper side of rail 1 by devices similar to those previously described.

It is possible to imagine all other positions of the core or of cores coated or carrying a variable number of conductors within rail 1.

These conductors can be located on both sides or on a single side of the or the several cores. In this latter case, the current outlets corresponding to one of the sides of the core will be replaced by simple supporting members.

Finally there has been shown in FIG. 5, another modification which gives another type of mobility to block 20 with respect to cradle 8. To this effect, block 20 rests not directly on the flat bottom of cradle 8 but in a seat 8' the upper side of which 28 is curved. Seat 8' is itself movable in one or several directions with respect to cradle 8. Block 20 is also movable in one or several directions in the curved recess 28 of seat 8'. This can in certain cases facilitate the maintenance of contact between outlets 22, 23, 24, or 25, and the plated conductors of core 11.

As indicated in the preamble this device can also be used with all other carriage devices supporting all types of hoisting and transporting machines which move along one or several guides by which they are supported or to which they are suspended. In particular this device can be used judiciously with vehicles moving on a rail with the interposition of an air cushion between the rail and the vehicle and this in order to provide electricity to said vehicle.

Finally the scope of the invention will not be avoided by using a similar device after simply rotating the same, that is by using an oblique or horizontal core and a block having an oblique or horizontal cut 21, the assembly having one or several characteristics of the present invention.

I claim:

1. In combination with a guide rail and a carriage travelling on said guide rail, means for supplying electric current to said carriage comprising an insulating core extending longitudinally of said guide rail and movably supported for movement laterally of said guide rail, at least one conductor extending longitudinally on and carried by said core, a cradle fixedly carried by said carriage, an insulating block resting in said cradle and straddling said core and at least one contact carried by said block and resiliently pressed into engagement with said conductor on said core.

2. A combination according to claim 1, in which said core is flexible.

3. A combination according to claim 1, in which said core is movably suspended from said rail for movement laterally of said rail.

4. A combination according to claim 1, in which said core is flexible and is flexibly suspended from said rail.

5. A combination according to claim 1, in which a plurality of conductors are provided on the same side of said core and are separated from one another by an intervening longitudinally extending insulating projection on said core.

6. A combination according to claim 1, in which said rail is of channel cross section with opposite side portions, a top portion connecting said side portions and inturned bottom flanges

projecting inwardly from said side portions, said core being suspended from a central portion of said top portions, said carriage having load carrying wheels running on said flanges and extending upwardly above said core.

7. A combination according to claim 1, in which said block is laterally movable in said cradle.

8. A combination according to claim 1, in which said block is laterally tiltable in said cradle.

9. In combination with a guide rail and a carriage running on said guide rail, means for supplying electric current to said carriage comprising an insulating core extending longitudinally of said guide rail and supported thereby, at least one conductor extending longitudinally on and carried by said core, a cradle fixedly carried by said core, an insulating block resting in said cradle and straddling said core and at least one contact carried by said block and resiliently pressed into engagement with said conductor on said core, said block being laterally movable in said cradle.

10. A combination according to claim 9, in which said cradle has a bottom portion on which said block rests, end portions constraining said block in a longitudinal direction and side portions limiting lateral movement of said block in said

cradle.

11. A combination according to claim 9, in which said cradle and block have interengaging surfaces at least one of which is curved to permit lateral tilting of said block in said cradle.

12. The combination of a rail of channel cross section having side portions, a top portion connecting said side portions, and inturned bottom flanges projecting inwardly from said side portions, an insulating core suspended from said top portion in said channel between said side portions, at least one conductor extending longitudinally of and carried by said core, a carriage having load carrying wheels running on said flanges and extending upwardly substantially to said top portion of the rail, an insulating block of U-shaped cross section straddling said core, said block being disposed between said wheels and being supported by and movable longitudinally with said carriage, at least one contact carried by said block and resiliently pressed into engagement with said block, and said core and said block being movable relative to each other laterally of said rail.
